UNITED STATES PATENT OFFICE.

THOMAS H. QUINN, OF CLEVELAND, OHIO.

WHEEL-FENDER.

SPECIFICATION forming part of Letters Patent No. 787,051, dated April 11, 1905.

Application filed December 17, 1904. Serial No. 237,261.

To all whom it may concern:

Be it known that I, THOMAS H. QUINN, a citizen of the United States, residing at Cleveland, in the county of Cuyahoga and State of Ohio, have invented new and useful Improvements in Wheel-Fenders, of which the following is a specification.

This invention is a wheel-fender particularly adapted for street-railway cars. It includes a front fender and a side fender on each side, these fenders being of the lift-and-drop kind, actuated either by contact with an object or by the motorman of the car.

The invention includes a novel arrangement of fenders and also novel means for latching the same so that they will drop into position to catch a body or object on the track.

In the accompanying drawings, Figure 1 is a perspective view showing the front fender and one side fender in raised position. Fig. 2 is a perspective view of one side fender in dropped position. Fig. 3 is a detail in perspective, illustrating the latch arrangement for controlling the drop of the fenders. Fig. 4 is a detail in perspective, illustrating the operation of the latches by means of a connection with the reversing-lever of the controller of the electric motor.

Referring specifically to the drawings, 1 indicates a front horizontal fender, at the rear of which is an upright fender or guard 2, pivoted to the front fender at 4.

8 indicates two steel supporting-bars, which run lengthwise under the front fender and under the platform of the car, being attached at the rear end to a rod 8^a, supported on the hangers 43, one at each side of the car-platform.

At the front of the fender 1 is a rod 5, covered with rubber, and this rod is connected to two sliding rods 7, which are movable lengthwise and operate to trip the supporting devices for the fenders, so that they will drop. To this end said rods 7 are provided with 10 stops 9, arranged to strike the lower ends of angular hangers 11, which are connected at 10 to a cross-bar 15, which is supported by a rod 16, extending vertically through the car-platform. The rod 15 turns in the connec-

tion 16^a at the lower end of the rod. The 50 hangers 11 normally support the fender 1. When a body is struck by the bar 5, the rods 7 slide back, causing the stops 9 to strike and swing back the hangers, allowing the fenders 1 and 2 to drop to the ground.

55

The side fenders are indicated at 3, one on each side. Each of these is hinged, as at 37, to a loop 38 on the bars 8, and they swing up and down on said hinges.

At 43 are indicated hangers, having on the 60 inside angular projections 34, which support the sliding bolts 35, which are connected at their ends to a cross-bar 32, extending across under the platform behind the rear ends of the rods 7. These rods are also connected at 65 the rear ends by a cross-bar 33.

30 indicates a bar hinged at 31 to the car-platform and depending between the cross-bars 32 and 33.

The side fenders 3 are normally supported 70 by the latch-bolts 35. When the rods 7 are shoved back, the cross-bar 33 hits the depending bar 30 and pushes it against the bar 32, which is thus forced backwardly and retracts the bolts 35, allowing the side fenders to fall 75 to strike and rest upon feet 36, projecting at the lower ends of the hangers 43. These side fenders are located directly in front of the wheels and serve to prevent persons or objects from rolling thereunder.

80

It will be seen that by the construction above described the impact of the bar 5 against a person or object on the track drops all three fenders.

Means are also provided and will now be 85 described for dropping the fenders by the motorman. The rod 16, which supports the hangers of the front fender, has a loop 16^b at the top, which is hooked upon a latch 42, pivoted at the top of a standard 17, supported on 90 the car-platform adjacent the controller, which is indicated at 23, and this latch is normally held by a pin 18, which is connected by a chain 20 to the reversing-lever 21 of the controller. When the motorman desires to stop 95 the car and drop the front fender in an emergency, the swing of the reversing-lever will pull out the pin 18, allowing the latch 42 to

tip and drop the rod 16, and consequently the front fender and also the side fenders through the connecting-wire 27^a.

The side fenders may be operated by the 5 motorman by means of a treadle 24, connected to a bell-crank lever 26, which in turn is connected by a wire 27, passing over a pulley 29, to a swinging arm 30. Pressure on the treadle causes the arm 30 to swing back, forcing the 10 bar 32 backwardly, and with it the bolts 35, thereby releasing the two side levers.

What I claim as new, and desire to secure by Letters Patent, is—

1. The combination of a front and two side 15 fenders arranged to lift and drop, of an impact-bar before the front fender, and means actuated by said bar to drop all of the fenders.

2. The combination of a front and two side 20 fenders arranged to lift and drop, and means on the car, adapted to be actuated by the motorman, to drop said fenders.

3. The combination with a car having a controller thereon, of a fender arranged to lift and drop, and means connected to the revers-

ing-lever of the controller to drop the fender 25 when said lever is turned.

4. The combination with a lift-and-drop fender, of a supporting - hanger therefor, and means constructed to be actuated both by impact with an object on the track, and by a person on the car, to release the hangers and drop the fenders. 3c

5. The combination with the hinged side fenders, sliding bolts supported on the car and arranged to hold up the fenders, an impact-bar at the front of the car, a man-operated device on the car-platform, and connections between said bolts and the impact-bar and device, constructed to draw the bolts and drop the fenders by operation of either the said 4c impact-bar or the device.

In testimony whereof I have signed my name to this specification in the presence of two subscribing witnesses.

THOMAS H. QUINN.
